UNITED STATES PATENT OFFICE

BEATRICE P. SCOTT, OF MARBLEHEAD, MASSACHUSETTS

STENCILING

Application filed March 31, 1927. Serial No. 180,073.

This invention relates to improvements in the art of stenciling.

It is an object of the invention to provide a means for making temporary figures and 5 designs upon suitable surfaces by using dry and non-sticky powders in lieu of the paints hitherto employed.

It is a further object to provide a stencil arrangement adapted primarily for the use of 10 children, although capable of more extended and serious applications.

The usual process of stenciling involves the use of a thick wet paint or pigment-paste which is applied to a surface through an 15 apertured sheet whose cut-out portions form the design or character it is desired to produce. Such an apertured sheet once applied to a surface, cannot be removed readily without smearing the design produced and unless allowed to dry when so removed it is apt 20 to soil objects with which it comes in contact. The stenciled object likewise must be handled carefully until the paint is dry, and the same surface obviously cannot be used repeatedly 25 to receive stenciled characters. These defects render the usual stenciling process and paints entirely unsuitable for the use of children.

The present invention contemplates the use 30 of a suitable dry and non-viscous powder instead of a wet viscous paint or paste. This powder, combined with a novel method of applying the same with a stencil screen of more or less usual construction, provides a 35 stenciled silhouette which is dry when applied, is sufficiently adherent to the surface to which it is applied to withstand jars and vibration and remains indefinitely on the surface if not disturbed, and yet can be rubbed 40 cleanly off, or otherwise removed, at will so that the same surface can be used repeatedly to receive the stenciled characters. The powder composing the stenciled character is such that it does not stain any usual surface 45 with which it comes in contact and can be removed by a cloth or brush or in any other convenient manner. The process forming the object of this invention as well as the materials used therein, are therefore, well 50 suited for the use of small children who are

heedless, usually, of the possibility of damaging surfaces which appear to them to be suitable for the application of stenciled designs.

The invention is illustrated in the accompanying drawing in which

Fig. 1 shows the prepared stencil in its raised position,

Fig. 2 illustrates the same in its applied position, while

Fig. 3 represents a surface to which the design carried by the stencil has been transferred.

Referring in detail to the drawing in carrying out my process, I employ a stencil 65 which comprises a rigid supporting frame 1 over which is tightly stretched a sheet of screen-like textile material 2 such as bolting cloth or similar material characterized by having a plurality of fine and closely spaced openings therethrough. In lieu of bolting cloth, a sheet of muslin can be used although bolting cloth is preferred. This sheet forms a screen on which the design to be stenciled is applied and the interstices of the screen 70 around the borders of the design and at those portions of the design that are not desired to be printed are filled in or sealed with a paint or a glue so that the perforations of the screen 75 are open only at those portions of the design adapted to be imprinted on the surface to which the stencil screen is applied. Thus, in the drawing, Fig. 1, 3 represents the design while 2 represents the sealed interstices. The stencil frame is then applied to the surface to be ornamented 5, the screen being 80 placed in intimate contact with the surface. A suitable powder is applied to the inner face of the stencil screen within the frame, and is rubbed into the interstices of the screen 85 by a wad of soft cloth or a powder puff 4. The powder may be sifted onto the screen or it may be deposited first on the wad of cloth or powder puff. All portions of the screen bearing the design are rubbed repeatedly 90 with the powder applicator with reasonable but not too heavy a pressure during which time the stencil screen is held immovable upon the surface 5. The stencil screen is 95 thereupon removed and it will be found that

the powder has gone through the open meshes of the screen and has adhered to the surface leaving a powder outline or silhouette of the design. The powder adheres quite strongly to the surface and will remain thereon indefinitely if not disturbed. It may be brushed off by the hand or a cloth thus leaving the surface in its original condition. The dry or non-viscous powders of many substances may be used. Cornstarch is very satisfactory. Talcum powder, flour, and powdered chalk are also satisfactory. A wet powder, or one having large flakes or granules cannot be used satisfactorily. The powder may be suitably colored if desired and quite artistic effects may be produced by properly selecting the color of the powder and the back ground of the surface on which the design is to be stenciled. Multi-colored designs may be produced by rubbing one portion only of the stencil with a powder of one color and another portion with a powder of another color.

It is found that powder adheres better to some surfaces than to other surfaces. The powder seems to adhere to polished metal surfaces and to varnished surfaces, whether smooth or somewhat rough and irregular. It will also adhere to glass. The powder adheres less strongly to certain kinds of glazed papers or paste-boards but can be made to adhere strongly thereto by first rubbing the paper with the hand or with a cloth to impart a uniform electrostatic charge to the paper, whereupon the powder is caused to adhere very strongly and indefinitely to the paper.

I am aware that it has been common practice to make stenciled designs by forcing a thick paint or pigment through a screen of similar nature. The method of applying paint, however, is materially different from my process, of applying powder. In applying paint, a squeegee, or sometimes a roller, of the full width of the design is employed. Thick paint is spread onto the screen at one end in front of the squeegee and the squeegee is pressed heavily down upon the screen and is drawn once only across the screen and the screen is then removed from the surface. If it is attempted to rub in the paint by repeatedly stroking the squeegee back and forth it is found that the design becomes blurred.

I find that I cannot apply the powder by a squeegee or roller. The powder will not adhere to the surface except possibly in spots. A brush is not satisfactory as a powder applicator as it produces a spotty silhouette, wherein the powder is unevenly deposited. I find that rubbing the screen repeatedly with the powder puff or cloth wad is the only method of which I am aware that will cause the powder to adhere to the surface. I am of the opinion that the repeated rubbing action electrifies or imparts a uniform electro-static

charge to the powder or to the material on which the screen is placed and so causes the powder to adhere to the surface of the material when the screen is removed. As evidence of this is the fact that some surfaces that will not ordinarily take the powder are caused to do so by preliminarily rubbing them to impart an electric charge thereto. The mechanism of my process, of course, is entirely different from that producing the adherence of paint, which owes its adherence to its viscous nature. 70 75

I claim:

1. The process of stenciling a design upon the surface of an object which consists in imparting an electric charge to the surface of the object by rubbing it, applying a dry powder to the surface through a design-bearing stencil screen applied to the surface by repeatedly rubbing the powder through the screen and onto the electrified surface, and removing the screen from the surface. 80 85

2. The method of applying a design to the surface of an object which consists in setting up a substantially uniform electrical charge on said surface and rubbing a dry powder through a design bearing stencil screen upon said surface. 90

3. The method of applying a design to the surface of an object which consists in rubbing a homogeneous dry powder through a stencil and upon said surface to produce the desired design and simultaneously set up a static charge to effect the adherence of the powder. 95 100

4. The method of making a temporary design which consists in placing a stencil over a surface to receive the design and simultaneously creating an electrical charge on said surface and rubbing a dry powder through said stencil to said surface. 105

5. The method of creating a design upon a surface consisting in mechanically distributing a dry powder in to the form of the desired design and creating a uniform static charge to effect the adherence of said powder to said surface. 110

In testimony whereof, I have signed my name to this specification.
